CONVEYER

Roger K. Hubbell, Newton, Mass., assignor, by
mesne assignments, to Conveyor Specialty
Company, Inc., Quincy, Mass., a corporation
of Massachusetts

Application July 20, 1946, Serial No. 685,265

3 Claims. (Cl. 198—19)

1

This invention relates to power-driven conveyors of the type employing an endless belt or chain. The invention is more particularly concerned with an improved conveyor or conveyor system which can be altered from time to time to suit changes in the conditions of use. One such variation is an increase or decrease in the length of the conveyor. Another variation is the addition or subtraction of shelves on one or both sides of the belt or chain. These variations may be made at the place where the conveyor is in use by proper substitutions and rearrangements of component parts kept in stock by the user or obtained from the maker from time to time as needed. To these ends, there is provided a basic unit which can be used alone or combined with one or more like units to increase the length of the conveyor. End-roll assemblies are provided for attachment to the ends of a single basic unit or to any desired multiple of the basic unit. In other words, a single pair of end-roll assemblies will serve for one or more basic units united end-to-end, and then equipped with a belt or chain to run on the end rolls. Similarly, side shelves maintained in stock by the user or obtained from time to time from the maker may be added to the basic unit on one or both sides, or removed when no longer needed.

The invention will be understood by reference to the following description when taken in connection with the accompanying drawings of certain specific embodiments thereof, while its scope will be pointed out more particularly in the appended claims.

In the drawings:

Fig. 1 is a plan of a two-unit conveyor embodying one form of the invention;

Fig. 2 is a side elevation of the same;

Fig. 3 is a side elevation of a single-unit conveyor;

Fig. 4 is an end elevation as viewed from the right-hand end of either Fig. 1 or Fig. 3;

Fig. 5 is a vertical sectional view on line 5—5 of Fig. 2;

Fig. 6 is an elevation of a transverse bar for use with a basic unit having a single shelf attached thereto;

Fig. 7 is an elevation of a short transverse bar for use with a basic unit having no shelf attached thereto;

Fig. 8 is a vertical cross-section of the basic unit alone;

Fig. 9 is a vertical, longitudinal section on line 9—9 of Fig. 8;

2

Fig. 10 is a horizontal sectional view on line 10—10 of Fig. 2;

Fig. 11 is a horizontal sectional view on an enlarged scale illustrating one of the roll-adjusting devices shown in Fig. 10;

Fig. 12 is a plan of one of the end-roll assemblies;

Fig. 13 is a vertical sectional view on line 13—13 of Fig. 12;

Fig. 14 is a side elevation of the end-roll assembly.

Referring to the drawings, and having reference at first more particularly to Figs. 8 and 9, there is shown a basic unit 50 comprising a main frame 52 which in this example is in the nature of a specially formed channel bar or beam having a web 54 and two downwardly-directed flanges 56 provided with inwardly-directed lips 58. This main frame is appropriately supported as by legs, herein channel bars 60 snugly fitting between and suitably secured as by welding to flanges 62 of a transverse channel-bar 64 whose web 66 is secured as by bolts 68 to the lip 58 of the main frame 52. The web 54 of the main frame 52 is provided with a lengthwise depression 70 to receive a belt or chain hereinafter described, the depth of the depression being such that the upper surface of the belt or chain is in the same plane as the upper surfaces of those portions of the web 54 which lie at the sides of the belt or chain. Thus, articles resting upon the lateral margins of the web can be moved smoothly and without hindrance upon the belt or chain.

There are circumstances under which it is desirable to provide shelves along one or both sides of the main frame, upon which articles may be supported while being loaded upon or unloaded from the belt or chain. To this end, there is provided a shelf unit 72 (see Fig. 5) readily attachable to and detachable from either side of the main frame 52 of the basic unit 50. In the present example, the shelf unit 72 is in the nature of a specially formed bar having a web 74 having two downwardly-directed flanges 76 and 78, the latter having an inwardly-directed lip 80 horizontally aligned with the corresponding lips 58 of the main frame 52. The shelf unit or units are conveniently secured to the side or sides of the basic unit as by bolts 82 passing through flange 56 of the main frame 52 and flange 76 of the shelf 72.

The basic unit 50, with or without a shelf unit or units 72 may be used alone if of sufficient length for the particular circumstances, or it may be combined with one or more

basic units placed end to end, with the ends secured together by appropriate means such as those now to be described. In the case of a basic unit using two shelf units (see Fig. 5) there is provided a transverse attaching bar such as an angle bar 84 removably attached as by bolts 86 to the several lips 58 and 80, and having a downwardly-directed flange 88 provided with holes 90 to receive bolts to fasten the angle bar to a similar angle bar on the next unit. If there are shelf units on both sides as in Fig. 5, the attaching bar is of sufficient length for that purpose. If, however, a single shelf unit is to be used, a shorter angle bar 84A is provided, and if no shelf unit is to be used a still shorter angle bar 84B is provided. When two or more basic units, with or without shelf units are assembled end to end (see Figs. 1 and 2) bolts 92 passed through the attaching bars secure them together.

Where two or more basic units are to be combined, as in Figs. 1 and 2, for example, there is provided a belt (or chain) 94 of sufficient length, whereas if but one basic unit is to be employed a like but shorter belt is employed. Regardless of the number of basic units, there are employed but two end-roll assemblies, now to be described, which are readily attachable to and detachable from the basic units. So also, regardless of the number of basic units, there is employed but one power unit presently to be described, which, likewise, is readily attachable to and detachable from the basic unit.

In this embodiment, the two end-roll assemblies are alike, and one of them will now be described, reference being had at first to Figs. 12, 13 and 14. Two parallel, lengthwise members such as channel bars 96 (see Fig. 12) are definitely spaced and rigidly connected as by a cross member such as an angle bar 98 suitably secured as by welding its ends to the channel bars. The channel bars are further connected to each other by a shaft 100 (see Fig. 13) fixedly held in place as by screws 102 passing through horizontally elongated openings or slots 104 in webs 106 of the channel-bars (see Fig. 12) thereby to permit a slight angular adjustment of the shaft to ensure true-running of the belt. The screws 102 pass also through blocks 108 (see Fig. 14) adjusted lengthwise of the slots 104 by set-screws 110 threaded through studs 112 having threaded shanks 114 passing through the webs 106 and secured by nuts 116.

Turning on and about the shaft 100 is a roller 118, suitably crowned, and having at its ends disks 120 secured to hubs 122 which turn on the shaft and are held against axial displacement by collars 124 secured to the shaft as by set-screws 126. The webs 106 are provided with bolt holes 128 (see Fig. 14) to receive bolts, as hereinafter described, to hold the end-roll assembly in its place in the basic unit. The cross-sectional dimensions and the spacing of the channel bars 96 are such that the bars slide snugly into the basic unit (see Fig. 10) where they are held by bolts 130 passing through the bolt holes 128. They are further held by two of the hereinbefore described bolts 86 (see Fig. 5) which secure the transverse bar 84 to the basic unit 50.

In the embodiment now under discussion, the rolls of the end-roll assemblies are simply idlers and the belt 94 is driven by a power-unit 132 (see Figs. 2, 3 and 4) which is attachable to and detachable from the basic unit 50. Only one such power-unit is provided for the conveyor

whether there be one or more of the basic units. Power unit 132 (see Figs. 2 and 3) includes driven rolls 134, an adjustable take-up roll 136 and a fourth roll 138 which is also adjustable. Power may be furnished, for example, by an electric motor, mounted on the frame below the rollers, through a suitable reduction gear set carrying a sprocket wheel on its output shaft having a chain connection with sprocket wheels associated with the rolls 134. The frame of the power unit may be bolted to the rib 58 of the main frame member 52. By removing the bolts the power unit may be dismounted and transferred to another basic unit as circumstances may require in adding to or subtracting from the conveyor from time to time to accommodate changing conditions.

To expand the conveyor from one having a single basic unit as in Fig. 3 to one having two basic units as in Figs. 1 and 2, it is only necessary, first, to remove the left-hand end-roll assembly and the belt from the structure as organized in Fig. 3, second, add a second basic unit at the left of the first unit as in Figs. 1 and 2, third, bolt the two basic units together, fourth, mount the left-hand end-roll assembly in the left-hand end of the added basic unit, and fifth, reeve a longer belt into place as it appears in Figs. 1 and 2. Subsequent further lengthening of the conveyor can be accomplished in a similar manner. In any case, it is important to note that only two end-roll assemblies and only one power unit are required, regardless of expansion of the conveyor. The user can therefore maintain, in stock, extra basic units and extra shelf units (or order them from the maker) and re-organize the assembly from time to time as the needs of the business require.

If desired, instead of driving the belt in the manner indicated by Figs. 2 and 3, power may be supplied to one of the end rolls. In such case, the power unit may, with advantage, be part of the assembly and the opposite end-roll used as a take-up roll.

Powering of the belt by means of one of the end-rolls has some advantages for some classes of work. Thus when the belt is used for conveying sticky material and the belt is powered through the bottom lead, the top surface of the belt, coming into contact with the rolls of the power unit, may transfer material to the rolls and makes frequent cleaning necessary. However, the illustrated method has certain advantages for non-sticky materials. One of these advantages is that it has identical head and tail-roll assemblies.

A fabric or other similar belt may be and commonly is employed, though a link belt or a chain-type belt may be employed to advantage in some installations. In some cases, the top surface of the belt or chain is substantially flush with the longitudinal margins of the main frame, while in other cases the top surface of the belt is somewhat above the margins of the main frame. The lateral shelf units may be applied to either or both sides of the main frame of either embodiment of the invention at whatever point or points a shelf or shelves may be desired.

As should be apparent by now, the invention herein is characterized by the fact that various unit assemblies are organized for use in a single or a plural unit conveyor, with facilities for enabling the conveyor to be added to or subtracted from, or to be arranged and rearranged to suit.

changing conditions of use and with the utmost simplicity and convenience.

Having thus described two embodiments of the invention, what I claim is:

1. In a conveyor unit, the combination with an elongated frame member having a horizontal web portion and opposed flanges depending from the longitudinal margins of the web portion, said portion serving as a runway for a conveyor belt on use of the unit, of a work shelf having a horizontal web portion and opposed flanges depending from the longitudinal margins of the web portion, said shelf being detachably secured through one of its flanges to one of the flanges of said frame member, and tie means at one end of said frame member adapting the frame member for end-to-end connection with a similar frame member provided with complementary tie means.

2. In a conveyor unit, the combination with an elongated frame member having a horizontal web portion and opposed flanges depending from the longitudinal margins of the web portion, said portion serving as a runway for a conveyor belt on use of the unit, of a work shelf having a horizontal web portion and opposed flanges depending from the longitudinal margins of the web portion, said shelf being detachably secured through one of its flanges to one of the flanges of said frame member, and an attaching bar connecting the flanges of said frame member at one end thereof, said bar adapting the frame member for end-to-end connection with a similar frame member so equipped.

3. In a conveyor unit, the combination with an elongated frame member having a horizontal web portion and opposed flanges depending from the longitudinal margins of the web portion, said portion serving as a runway for a conveyor belt on use of the unit, of a work shelf coextensive with said frame member having a horizontal web portion and opposed flanges depending from the longitudinal margins of the web portion, said shelf being detachably secured through one of its flanges to one of the flanges of said frame member, and an attaching bar connecting the other flange of said shelf and the flanges of said frame member at one end of the unit, said bar adapting the unit for end-to-end connection with a similar unit so equipped.

ROGER K. HUBBELL.
